FIG 4a

FRANK B. SNYDER ^{Inventor}

By N. E. Gee

Attorney

UNITED STATES PATENT OFFICE.

FRANK B. SNYDER, OF ALTOONA, PENNSYLVANIA, ASSIGNOR OF ONE-HALF TO
NASSIF E. TROD AND ASSID E. TROD, BOTH OF ALTOONA, PENNSYLVANIA.

EXPRESS WAGON.

1,411,308.

Specification of Letters Patent. Patented Apr. 4, 1922.

Application filed July 21, 1921. Serial No. 486,492.

To all whom it may concern:

Be it known that FRANK B. SNYDER, a citizen of the United States, residing at Altoona, in the county of Blair and State 5 of Pennsylvania, has invented certain new and useful Improvements in Express Wagons, of which the following is a specification.

This invention relates to wagons and more particularly to an improvement in small express wagons of the type used by children 10 at play.

A primary object is to provide an improved means of mounting the wagon bed on the running gear in such a novel manner as to reduce shocks and the tractive effort necessary to move the wagon over rough places when loaded.

Another object of the invention is to provide a novel mounting for the bed whereby 20 the contents thereof can readily be discharged by elevating the front end of the bed.

With these and other objects in view, which will be more readily apparent as 25 the nature of the invention is better understood, the same consists in the novel construction, combination and arrangement of parts hereinafter more fully pointed out, illustrated and claimed.

It will be apparent to those skilled in the art, that the same is susceptible to structural changes and modifications without departing from the spirit or scope of the invention, but a preferred and practical embodiment of the invention is shown in the 35 accompanying drawings in which—

Figure 1 is a plan view of an express wagon having my improvements attached thereto.

Figure 2 is a side elevation of the wagon and parts shown in Figure 1 of the drawings.

Figure 3 is an end elevation of the parts shown in Figure 1 of the drawings.

Figures 4 and 4^a are plan and edge views 45 of the locking plates which may be disconnected when the wagon is used as a miniature dump wagon.

Figure 5 is an enlarged detail view of the 50 spring suspension which is used to carry the wagon bed and its load.

Similar reference numerals refer to similar parts throughout the several figures of the drawings.

In carrying the present invention into ef-

fect no change is contemplated or required in the usual construction of the bed or body of the wagon which may be designated in its entirety by the numeral 10. Accordingly it is proposed to mount the said body upon 60 a novel running gear or support carried by the front and rear axles 11 and 11^a having the wheels 12 thereon. Upon the front axle 11 is arranged a suitable bolster 13 which may be connected with the front axle in any 65 suitable manner as at 14.

The upper side of the bolster 13 preferably carries a transverse plate 15, the outer end of which has attached thereto the rearwardly extending frame bars 16 whose rear 70 ends may be connected directly to the rear axle 11^a to provide a rigid connection for the front and rear axles. At an intermediate point the side frame bars 16 are connected by a transverse fulcrum bar 17. 75 In front of the said fulcrum bar is arranged a spring abutment bar or its equivalent 18, the same being provided with openings adjacent the frame bar 16 to slidably accommodate the rods 19 carried by the 80 front ends of the body supporting bars 20. These rods 19 are surrounded by a coil spring 21 and carry at their lower ends abutment washers 22 for engaging the lower 85 end of the springs 21. As will be seen more clearly from Figure 5 the said springs 21 are confined between the side of the spring abutment member 18 and the abutment washer 22, whereby the upward movement of the forward ends of the bar 20, that is 90 the ends of the bars having the rods 19 connected thereto is resisted by the compressive force of the springs 21.

The rear ends of the bars 19 are pivotally connected as at 23 with the rear end of 95 the body 10, and since the bars 19 have a more or less fulcruming engagement with the bar 17, according to the strength of the springs 21 it will be apparent that the rear end of the body 10 has a resilient support 100 on the rear end of the frame. As the greater part of the weight is usually carried over the rear axle the advantages of this resilient mounting will be readily apparent.

For the purpose of holding the front end of the body 10 down to the running gear, any suitable and convenient form of lock may be provided. It is preferable, however, to use a simple form of lock that will readily per- 110

mit the body to be swung on the pivots 23 to permit the wagon to be used as a dump wagon. To that end the coupling plates 24 and 25 may be employed. These plates have 5 registering eye portions 26 and are respectively carried by the body 10 and the said frame bars 16, whereby they may be brought into registration to receive a pin, bolt or like locking device to hold the body level when 10 it is not desired to use the same as a dump wagon. By extracting the pins from the eyes 26 into locking plates the body will readily swing on the pivots 23 to provide the usual dump wagon effect.

15 Wagons built upon the above principle are easily operated over rough roads or streets and when used as a coaster the method of body support greatly facilitates the ease with which the same is operated, 20 while at the same time it eliminates the shocks and jars usually transmitted to the body of the vehicle.

I claim:

1. A combined coaster or express wagon 25 including a body, a running gear frame constituting a connector for the front and rear axles of the wagon, a body supporting unit having relatively pivotal engagement with the body and a fulcruming engagement with 30 the running gear, and spring means arranged between the body supporting unit and the running gear.

2. A combined coaster and express wagon including a body, a running gear arranged 35 in a substantially rearwardly inclining position, a relatively loose pivotal connection between the front end of the body and the front end of the running gear, and a resilient support arranged between the rear 40 end of the body and said running gear.

3. A combined coaster and express wagon including a body, a running gear arranged in a substantially rearwardly inclining position, a relatively loose pivotal connection between the front end of the body and the 45 front end of the running gear, and a resilient support for the body and said running gear, said support consisting of a bar having a pivotal connection with the body and a resilient fulcruming connection with the 50 running gear.

4. A combined coaster and express wagon including a body, a running gear arranged in a substantially rearwardly inclining position, a relatively releasable connection between the front end of the body and the 55 front end of the running gear, and a resilient support arranged between the rear end of the body and said running gear, said support including a transverse fulcrum bar, 60 a pair of body supporting bars pivotally connected at one end with the wagon body and resiliently connected at the other end with the running gear.

5. A combined coaster and express wagon 65 including a body, a running gear consisting of a rearwardly inclining frame, a bolster interposed between the front end of the frame and the front axle, and said frame consisting of oppositely arranged bars having 70 their front ends connected to said bolster and their rear ends connected to said axle, a releasable connection between the front end of the wagon body and the front end of the running gear frame, and a relatively 75 resilient connection between the rear end of the wagon and the said running gear frame.

In testimony whereof he affixes his signature.

FRANK B. SNYDER.
